DESIGN.

No. 15,368.

Aug. 26, 1884.

UNITED STATES PATENT OFFICE.

WILLIAM McCALLUM, OF YONKERS, NEW YORK, ASSIGNOR TO THE BIGELOW CARPET COMPANY, OF CLINTON, MASSACHUSETTS.

DESIGN FOR A CARPET.

SPECIFICATION forming part of Design No. 15,368, dated August 26, 1884.

Application filed June 27, 1884. Term of patent 3½ years.

To all whom it may concern:

Be it known that I, WILLIAM McCALLUM, a resident of Yonkers, in the county of Westchester and State of New York, have invented and produced a new and original Design for a Carpet, of which the following is a full description, in connection with the accompanying photograph, which represents a face view of my new design for a carpet.

10 This invention relates to a new ornamentation of the face of a carpet, oil-cloth, or analogous fabric.

In the accompanying photograph is shown the group A, decorated with star-like figures a, and having corner-pieces b, c, and d. The group B contains ornamental figures e and f, and at the corner has an ornamental figure, g. The group C contains ornamental figures, and has the figure h at the corner. Group D has a border, from which project the 20 conventional flowers i and ornament k. It also contains star-like ornaments and conventional flowers. E, F, and G are figures of a fanciful character, which are likewise decorated with ornaments. Among the groups A, B, C, and 25 D are interspersed arabesque-like figures and leaves and flowers.

I claim—

The design for a carpet, the same consisting of the figures A, B, C, D, E, F, G, a, b, c, d, e, 30 f, g, h, i, and k, substantially as shown.

WILLIAM McCALLUM.
